UNITED STATES PATENT OFFICE

HARRY R. DECKER, OF HOUSTON, TEXAS

PIPE HOLDING SLIP

Application filed September 27, 1926. Serial No. 137,913.

This invention relates to new and useful improvements in a pipe holding slip.

One object of the invention is to provide a slip of the character described specially designed to be inserted in a rotary table, around a pipe, for the purpose of suspending the pipe in a well bore, and is of such construction that it will grip the pipe to be held, uniformly all the way around and will thus not be liable to dent or crush the pipe.

Another object of the invention is to provide a slip of the character described formed of independent sections, each section embodying a plurality of independent, pipe engaging jaws, anchored in fixed relation to each other. It is desirable that these jaws be fixed in their holders so that they will be maintained in transverse alignment and will thus engage the pipe all the way around when the slip is inserted in the rotary table spider around said pipe. If the jaws are held loosely in the holders so that they have independent movement relative to each other, it will often happen that some of the jaws will drop down further into the rotary table spider than others and will consequently exert greater inward pressure on the pipe than the other jaws, or the jaws will assume a position in the spider which will not permit them to grip the pipe uniformly, and when the full weight of the pipe is sustained by the slip the pipe will be crushed, or dented, by reason of the unequal pressure of the jaws against it. Accordingly it is one of the main objects of this invention to provide a slip the jaws of whose sections are securely anchored in fixed relation to each other.

Another object of the invention is to provide a slip of the character described composed of independent sections, each section comprising upper and lower arcuate plates or anchors with a plurality of pipe engaging jaws between them and whose respective upper and lower ends are suitably secured to said anchors, with means for relieving said securing means from the strain of the load carried by the slip, to the end that they will not become broken or sheared off when the slip is subjected to the full strain of the load.

It sometimes happens that the jaws are subjected to a lateral strain, particularly when the slip sections are not disposed directly opposite each other, or not disposed in uniform spaced relation to each other 55 around the pipe. In the present instance means have been provided for transmitting this lateral strain from one jaw to the adjacent jaws directly rather than to the anchorage of said jaw to the holder so that the end 60 that said anchorage will not be broken or sheared.

A still further object of the invention is to provide a slip of the character described which is equipped with a novel type of handle 65 or bail for handling the slip sections independently.

With the above and other objects in view this invention has particular relation to certain novel features of construction, operation and arrangement of parts, an example of which is given in this specification and illustrated in the accompanying drawings, wherein:

Figure 1 shows a fragmentary plan view 75 of the slip.

Figure 2 shows a side elevation thereof, partly in section.

Figure 3 shows a fragmentary inside view 80 of one of the end jaws of a slip section.

Figure 4 shows a fragmentary inside view of one of the end jaws of a slip section showing also a fragmentary sectional view of the associated lower anchor.

Figures 5 and 6 show fragmentary plan 85 views of the respective lower end anchors, and

Figures 7 and 8 show side and sectional views, respectively, of said anchors.

Referring now more particularly to the 90 drawings, wherein like numerals of references designate similar parts in each of the figures. The numerals 1, 1 designate the arcuate upper end plates of jaw anchors of the respective slip sections and the numerals 95 2, 2, designate the respective arcuate lower end plates or jaw anchors. Each section of the slip includes a plurality of pipe engaging jaws 3, 3', the end jaws 3' of each section of the slip being substantially similar 100

to the other jaws but differing therefrom in certain particulars to be hereinafter mentioned. These jaws are substantially rectangular in cross section and are relatively thin and radially disposed and their outer edges converge downwardly to conform to the contour of the rotary spider which has a downwardly converging seat to receive said slip. The inner edges of the jaws are preferably transversely toothed to engage the pipe 4 to be suspended thereby. These teeth are straight, that is, they extend tangentially with respect to the surface of the pipe, as shown in Figure 4. With a light load only the central part of the teeth will engage the pipe but if the load is heavy the teeth will bite into the pipe for a greater length so that the greater the load of pipe, the greater the length of contact of the teeth with the pipe. This type of slip will hold the pipe against turning so that the upper sections of pipe may be unscrewed from the pipe, or additional sections added thereto without the use of back-up tongs to hold the pipe in the rotary table against rotation.

The outer edges of the jaws are disposed parallel with said teeth so that only the corners of said edges will engage the rotary spider and consequently the slip sections are not so liable to stick in the spider when it is desired to remove them. The upper ends of the jaws are fitted into radial grooves 5 in the under side of the anchors 1 and having the upwardly extending studs 6 which fit through corresponding openings 7 in the anchors 1 and which are secured therein in any desirable manner, as by the nuts 8 which are threaded on to said studs 6 and which are seated, or enclosed, in the countersunk recesses 9 in the upper sides of the anchors 1. The anchors 1 rest on the upper ends of the corresponding jaw 3, 3', and said upper ends of said jaws have the upward extensions 10, the outer edges of said extensions 10 converging upwardly and the inner sides of the anchors 1 being formed with upwardly converging bearing faces 1' which bear against said extensions 10 and prevent the jaws from moving radially under the stress of a load. The lower ends of the jaws 3, 3' are seated in the radial grooves 11, 11' of the lower jaw anchors 2 and suitable studs, or stud bolts, as 12, are secured to the lower ends of the jaws and are fitted through aligned bearings 13 in the corresponding jaw anchors 2 and receive the retaining nuts 13 which are threaded on to the lower ends thereof. The upper and lower ends of the jaws 3, 3' are thus seated in radial grooves in the upper and lower anchors and are held against circumferential movement relative to said anchors and relative to each other by the upper and lower spacers 14, 15, which are formed integrally with the respective anchors and which fit between the jaws at their upper and

lower ends respectively. The outer side of each anchor 2 has arcuate upstanding tenons 16, whose outer side is beveled inwardly, as at 17, and these tenons have the notches, or bearings 18, 18' aligned with the corresponding grooves 11, 11' and the lower ends of the jaws 3, 3' have the mortises 19, which receive said tenons when these jaws are seated in said notches. The outer edges of the jaws extend out slightly beyond the anchor 2 and the outer sides of the tenons 16 being beveled, when the slip is seated in the rotary spider and is under the stress of a load of pipe there will be an interlocking effect between said tenon and mortises which will tend to hold the corresponding anchor 2 up closely against the lower ends of the corresponding jaws and this will prevent any relative movement of said jaws and anchor 2 and will tend to protect the studs 12 from strain or shearing effect. The lower ends of the jaws 3, 3' are held against radial movement by reason of the fact that they abut against the outer ends 20 of the respective radial grooves 11, 11'.

It is to be noted from an inspection of Figures 3 and 4 that the end jaws 3' of each section have their outer sides counter-sunk at their lower ends as indicated by the numeral 20'. These counter sunk portions are provided to receive the upstanding lugs 21 at the ends of the anchors 2 to the end that each end jaw of the slip will be thoroughly braced against movement in any direction, the lugs 21 being countersunk into the jaws so that there will be no projection for one section of the slip to hang on when lowering them into the rotary spider.

The ends of each anchor 1 have the outside notches 22 which terminate in the upwardly and outwardly inclined shoulders 23. Each section of the slip is provided with a bail, or handle 24 of substantially an inverted U-shaped form and whose inner ends 25 are inwardly turned through the bearings 26 in opposing ends of the respective anchors 1. These bails, when not in use, will lie back in the notches 22, in substantially a horizontal plane beneath the upper surface of the anchors 1 and will thus be protected against breakage from the elevators or from other heavy objects in carrying on drilling operations and the shoulders 23 limit the range of movement of the handle upwardly toward the vertical axis of the slip.

The facing sides of the adjacent jaws may, if desired, be provided with lateral projections 27 which have abutting bearing faces, as shown in Figure 1. These are provided so that any twisting or lateral strain to which one of the jaws may be subjected will be transmitted directly to the other jaws rather than to the studs 12 so as to prevent the shearing or breaking of said studs.

What I claim is:—

1. A pipe holding slip comprising a plu-

1. A pipe holding slip comprising a plurality of sections, each section including a holder composed of an upper and a lower arcuate anchor whose inner sides have radial grooves and a plurality of jaws between said anchors whose ends are fitted into the corresponding grooves, means securing said jaws to said anchors, the upper ends of said jaws having upward extensions which abut against the inner side of said upper anchor and the lower anchor having outside abutments against the inner sides of which the lower ends of the respective jaws abut, said upper anchor and the abutments of the lower anchor being thus adapted to prevent the outward, or radial, movement of the jaws relative to said holder, the outer sides of the end jaws of said sections being countersunk at their lower ends and upwardly extending projections carried by the lower anchor and resting in said respective countersunk portions.

2. A pipe holding slip comprising a plurality of sections, each section including an upper and a lower arcuate anchor, a plurality of jaws whose respective ends are secured to said respective anchors, said anchors and jaws having abutting parts disposed to prevent the outward, or radial movement of the jaws with respect to said anchors and projections carried by the facing sides of said jaws which abut.

3. A pipe holding slip comprising a plurality of sections, each section including an upper and a lower arcuate anchor, a plurality of jaws whose respective ends are secured to said respective anchors, said anchors and jaws having abutting parts disposed to prevent the outward, or radial movement of the jaws with respect to said anchors, spacers carried by said anchors and located between the adjacent jaws at their upper and lower ends which are provided to prevent the lateral movement of said jaws relative to the anchors.

4. A pipe holding slip comprising a plurality of sections, each section including an upper and a lower arcuate anchor, a plurality of jaws whose respective ends are secured to said respective anchors, said anchors and jaws having abutting parts disposed to prevent the outward, or radial, movement of the jaws with respect to said anchors, upwardly extending arcuate tenons integral with the lower anchor whose outer sides are inwardly beveled, the lower ends of the corresponding jaws having correspondingly shaped mortises in which said tenon fits.

5. A pipe holding slip comprising a plurality of sections, each section including an upper and a lower arcuate anchor, a plurality of jaws whose respective ends are secured to said respective anchors, said anchors and jaws having abutting parts disposed to prevent the outward, or radial movement of the jaws with respect to said anchors, arcuate tenons carried by one of said anchors whose

outer sides are inwardly beveled, the adjacent ends of the jaws having correspondingly shaped mortises adapted to receive said tenon.

6. A slip section comprising an upper and lower arcuate anchor, said anchors forming a holder, a plurality of jaws substantially rectangular in cross section, permanently secured in and radially disposed in said holder, means securing respective ends of the said jaws to the corresponding anchors and means carried by the anchors and abutting the outer edges of the jaws, at their upper and lower ends, and means abutting the sides of the said jaws at their upper and lower ends, said abutting parts retaining the jaws against movement with respect to the holder.

7. A slip section comprising an upper and a lower anchor and pipe holding jaws mounted between them, said upper anchor having outside end notches adjacent its respective ends, bearings extending inwardly from said notches, a U-shaped bail whose ends work in the respective notches and are inwardly turned into said bearings.

8. A pipe holding slip comprising a plurality of sections, each section including an upper and lower arcuate anchor, a plurality of jaws whose respective ends are secured to said respective anchors, said anchors and jaws having abutting parts disposed to prevent the outward or radial movement of the jaws with respect to each other, and abutting means carried by the facing sides of the jaws.

9. A pipe holding slip comprising a plurality of sections, each section including an upper and lower arcuate anchor, a plurality of jaws whose respective ends are secured in radial grooves in the respective anchors, said anchors and jaws having abutting parts disposed to prevent the outward or radial movement of the jaws with respect to the anchors and abutting means carried by the facing sides of the said jaws.

10. In a pipe holding slip a section having a plurality of jaws, an anchor to which said jaws are attached, a handle pivotally connected to the anchor to swing on a substantially horizontal axis and an abutment on the anchor to limit the range of movement of the handle upwardly toward the vertical axis of the slip.

11. In a pipe holding slip, a slip section, a handle pivotally connected to the upper end of said section to swing on a substantially horizontal axis and an abutment on the slip section to limit the range of movement of the handle upwardly toward the vertical axis of the slip.

In testimony whereof I have signed my name to this specification.

HARRY R. DECKER.
